UNITED STATES PATENT OFFICE.

MARIE JOSEPHINE CULLY, OF CHICAGO, ILLINOIS.

HAIR-WAVING DEVICE.

1,329,378.

Specification of Letters Patent.

Patented Feb. 3, 1920.

Application filed March 21, 1919. Serial No. 284,026.

To all whom it may concern:

Be it known that I, MARIE JOSEPHINE CULLY, a citizen of the United States, and a resident of the city of Chicago, in the county of Cook and State of Illinois, have invented certain new and useful Improvements in Hair-Waving Devices; and I do hereby declare that the following is a full, clear, and exact description of the same, reference being had to the accompanying drawings, and to the numerals of reference marked thereon, which form part of this specification.

This invention relates to hair waving devices in which the hair is bent around a heated iron or the like and held in that position until the hair has acquired the desired permanent set.

Hitherto with devices of this character the hair has been bent laterally around the iron so as to produce waves in the hair lying wholly in a plane perpendicular to the axis of the iron. This gives the hair an objectionable artificial appearance not possessed by naturally wavy hair.

It is an object, therefore, of my invention to provide means for waving the hair in two planes simultaneously and thereby giving the hair an irregular cork screw form which is very pleasing to the eye.

Other and further important objects of the invention will be evident from the disclosure in the drawings and specification.

The invention (in a preferred form) is illustrated in the drawings and hereinafter more fully described.

In the drawings:

Figure 1 is a perspective view of a device embodying my invention.

Fig. 2 is a plan view of the underside of the device.

Fig. 3 is a side view of the device.

Fig. 4 is a plan view of a part of the device.

Fig. 5 is an end view of the same.

Fig. 6 is a section on the line 6-6 of Fig. 2.

Fig. 7 is a section on the line 7-7 of Fig. 2.

As shown in the drawings:

The device comprises an iron 1, slivably mounted on a plate 2, which in turn is provided with a handle 3. Pivoted at 4 to this handle 3 is a second handle 5, which carries a pair of knife-like members 6 adapted

to be moved toward and away from the iron by means of the handles 3 and 5.

The iron is rounded on one side so that by moving the member 6 toward the iron the hair may be drawn across that rounded portion and thereby given a wave in a plane perpendicular to the axis of the iron.

In order that the hair may be simultaneously waved in a second direction the iron is formed with a series of transverse corrugations or ridges 7, between which the hair is drawn by the action of the members 6.

Similarly the plate 2 is flanged laterally at 8 and in the edge of such flange a series of corrugations 9 are formed. The movement of the members 6 toward the iron brings the hair into engagement with these corrugations 9 as well as with the corrugations 7. Consequently if the iron is moved relatively to the plate 2, the hair will be drawn into the position shown in Fig. 1 and hence acquire a wave in a direction longitudinal with respect to the iron.

This relative movement of the iron and the plate may conveniently be accomplished by slotting the plate as at 10 and providing lugs 11 on the back of the iron having slots 12 for sliding engagement with the edges of this slot. The movement of the iron along the plate may be readily controlled by a lever 13, pivoted to the plate at 14 and connected at 15 to a link 16. This link is pivotally attached at 17 to one of the lugs 11. A finger hold 18 may conveniently be provided at the end of the lever 13.

Care must be taken to prevent pull or tearing of the hair by the members 6. For this purpose ample clearance should be provided between these members and the iron on one side and the flanges 8 on the other. Further clearance should be provided between the inner edge of the member 6 and the plate 2, as shown in Fig. 6, when the handles 3 and 5 are pressed together. To insure such clearance the handles are arranged to contact with each other, as at 20, when the members 6 have been brought into the position shown in Fig. 6, relatively to the iron and plate.

The operation is as follows:

The handles 3 and 5 are separated to move the members 6 away from the iron sufficiently to allow the strands of hair to be waved to be placed therein. The handles are then brought together thereby moving

the members 6 into the space between the iron 1 and the flanges 8. This action draws the hair over the iron and also brings it into engagement with the corrugations 7 and 9, 5 on the iron and flanges 8, respectively. The lever 13 is then operated to move the iron longitudinally from the position shown in dotted lines in Fig. 2 to that shown in full lines in the same figure. This brings the 10 hair into the position illustrated in Fig. 1. After allowing time for the hair to acquire a permanent set the handles 3 and 5 are separated and the device brought into engagement with a further section of hair 15 when the operation is repeated.

Preferably the iron is moved relatively to the plate in opposite directions in successive operations so as to bend the hair first up and then down and so produce the desired wave 20 form. If the hair is naturally wavy, the iron is, of course, used in such a way as to augment the natural tendency to wave.

I am aware that various details of construction may be varied through a wide 25 range without departing from the principles of this invention and I therefore do not pur- pose limiting the patent granted otherwise than necessitated by the prior art.

I claim as my invention:

30 A hair waving device comprising an iron

having transverse corrugations thereon, angle bars on either side of the iron having corrugations in the edges parallel to the sides of the iron, said iron being arranged for sliding engagement with the other edges of 35 the angle bars, hair engaging fingers pivotally connected to the angle bars adapted to enter the space between the iron and the corrugated edges of said bars and thereby draw the hair downward over the iron to 40 wave it in one direction and simultaneously bring the hair into engagement with the corrugations on both the iron and said bars, means for moving the fingers, means independent of the last mentioned means for 45 subsequently moving the iron longitudinally with respect to the angle bars to wave the hair in a second direction, a stop for limiting movement of the fingers toward the angle bars and thereby insuring ample clear- 50 ance under the fingers when in operative position to allow the hair to slide therearound.

In testimony whereof I have hereunto subscribed my name in the presence of two subscribing witnesses.

MARIE JOSEPHINE CULLY.
